UNITED STATES PATENT OFFICE.

THOMAS A. LEGGE, OF CHICAGO, ILLINOIS, ASSIGNOR TO THE ADAMS & WESTLAKE COMPANY, OF CHICAGO, ILLINOIS, A CORPORATION OF ILLINOIS.

LAVATORY.

1,067,261.

Specification of Letters Patent.

Patented July 15, 1913.

Application filed May 17, 1913. Serial No. 768,367.

To all whom it may concern:

Be it known that I, THOMAS A. LEGGE, a citizen of the United States, and resident of Chicago, county of Cook, State of Illinois, have invented certain new and useful Improvements in Lavatories, of which the following is a specification, and which are illustrated in the accompanying drawings, forming a part thereof.

10 The invention relates to lavatories and more particularly to those in which the bowl or basin is constructed to be turned against the wall when not in use.

15 The object of the invention is to provide a lavatory of the type described which shall be of simple and efficient construction, and the invention more particularly contemplates a lavatory provided with improved means for holding the bowl in both the 20 folded and service positions.

25 In the accompanying drawings, Figure 1 is a front elevation showing a form of lavatory embodying the features of improvement provided by the invention and some 30 of the parts being broken away. Fig. 2 is a side elevation of the same partly in section, the service position of the bowl being indicated by dotted lines, and Fig. 3 is a detail sectional view showing a form of connecting link which may be used upon the device.

35 A fixed wall plate is indicated in the drawings at 10. This plate may be of any convenient form but is preferably constructed to support a waste receiver 11 upon its front face and to serve as an abutment for the rim of the bowl 12 when the latter is folded to an upright position above the waste receiver. The waste receiver 11 is 40 shown as taking the form of a hopper having a drain 13 at its lower end.

45 The bowl 12 is conveniently connected to the front wall of the waste receiver as by hinges 14 and 15. Preferably the hinges 14, 15 are secured against the under side of the bowl a short distance in advance of its rear edge. This location of the hinges provides that a portion of the bowl may project over the waste receiver at all times.

50 When so arranged an opening 16 is preferably provided in the wall of the bowl adjacent its rim and in rear of the hinge line. This opening serves both as an overflow when the bowl is in service and as a discharge opening for the contents of the bowl

into the waste receiver when the bowl is folded to the upright position. A handle, 17, will usually be provided for manipulating the bowl. As shown, this is secured against the front wall of the bowl adjacent 60 its rim.

In carrying out the invention a pair of elastically extensible links, 18, are provided, one being located at each side of the bowl. As shown, each of these links is composed 65 of telescopically connected sections 19 and 20. The section 19 of each link conveniently takes the form of a rod and has one end pivotally attached to the bowl, 12. For this purpose a bracket, 21, is secured 70 against the under side of the rim of the bowl. The section 20 of each link 18 is made tubular for receiving an end portion of the section, 19. This section of each link is most desirably provided with a head, 22, 75 the same being fixedly applied by the use of a screw threaded shank 23 which enters the end of the section. Section 20 of each link is pivotally attached to the wall plate 10 below the level of the bowl. As shown 80 a bracket lug 24 is mounted upon the wall plate 10, at each side of the waste receiver 11, and is pivotally united with the head portion 22 of the section 20 of the corresponding link. 85

A spring 25 is housed within the tubular section 20 of each of the links 18 for controlling the relative telescopic movement of the sections. The section 20 is shown as being of reduced diameter adjacent one end to 90 provide an abutment shoulder 26, for the corresponding end of the spring. The other end of each spring reacts against an abutment shoulder formed upon the section 19 of the corresponding link. This latter 95 abutment shoulder is conveniently provided by the use of a washer 27, mounted upon the part 19 adjacent its outer end and held against displacement thereon by means of a pin 28 set through the section beyond the 100 washer.

105 Preferably the parts are so proportioned that the inner end of the threaded shank 23 of the head 22 of the section 20 of each link serves as a stop for engagement by the end 105 of the section 19 of the corresponding link when the bowl 12 is in the horizontal position of service indicated by the dotted lines in Fig. 2. The links thereby serve as braces for supporting the bowl in the horizontal 110

position. Most desirably, also, each spring 25 is so constructed as to be held against complete expansion by the engagement of the end of the corresponding section 19 with the 5 said stop. Vibration of the bowl when in the horizontal position is thereby also prevented.

When the bowl is folded to an upright position against the wall plate 10, the links 18 10 are moved across the line of the hinges 14, 15. The elasticity of the springs 25 accordingly serve to urge the rim of the bowl against the wall plate for retaining the bowl in the said upright position. If desired, a 15 faucet 29 may be provided for filling the bowl. As shown, this faucet is so located as to be covered by the bowl when the latter is folded to the upright position. For this purpose it is mounted upon the part of the 20 wall plate 10 which is above the waste receiver 11, and is so jointed as to be capable of being folded against the wall plate when not in use and to be extended to a position over the bowl when the latter is to be filled. 25 In this respect the faucet is of a well known form of construction, the flexing of its joints serving to operate a valve for controlling the water supply.

I claim as my invention—

30 1. In a lavatory, in combination, a waste receiver, a bowl hingedly connected to the front edge of the waste receiver and movable between a horizontal position in front of the waste receiver and a vertical position above the waste receiver and an elastic link having its ends respectively connected to a side of the bowl and a side of the waste receiver.

2. In a lavatory, in combination, a basin 40 hingedly connected to a fixed support, and an elastic link connected to the basin and to the support at points separated from the hinge and movable across the line of the hinge during the turning of the basin.

45 3. In a lavatory, in combination, a waste receiver, a bowl having a discharge opening in its rear wall, a hinge connecting the front edge of the waste receiver and the under side of the bowl and an elastic link having 50 its ends respectively connected to a side of the bowl beyond the said hinge from the waste receiver and to a side of the waste receiver below the said hinge.

4. In a lavatory, in combination, a wall 55 plate, a waste receiver mounted on the wall plate and projecting in front of the same, a

basin hinged to a projecting part of the waste receiver for movement between a horizontal position in front of the waste receiver and an upright position above the 60 waste receiver, the rim of the basin contacting with the wall plate in the last-mentioned position and an elastically extensible link connecting the wall plate and basin, the said link acting as a brace to support the basin in 65 its said horizontal position and being moved across the line of the hinge during the raising of the basin.

5. In a lavatory, in combination, a waste receiver, a bowl having a discharge opening 70 in its rear wall, a hinge connecting the front edge of the waste receiver and the underside of the bowl, and an extensible link connected at one end to the bowl at a point beyond the said hinge from the waste receiver and 75 at the other end to the waste receiver at a point below the hinge, said link serving as a brace to support the bowl when contracted.

6. In a lavatory, in combination, a waste receiver, a bowl having a discharge opening 80 in its rear wall, a hinge connecting the front edge of the waste receiver and the underside of the bowl, and an elastically extensible link connected at one end to the bowl at a point beyond the said hinge from the waste 85 receiver and at the other end to the waste receiver at a point below the hinge, said link serving as a brace to support the bowl when contracted, and being moved across the line of the said hinge during the raising of the 90 bowl.

7. In a lavatory, in combination, a wall plate, a waste receiver mounted thereon and projecting in front of the same, a bowl, a hinge connecting the rear edge of the bowl 95 and the front edge of the waste receiver, and an elastically extensible link connected at one end to the bowl at a point beyond the said hinge from the waste receiver and at the other end to the waste receiver at a 100 point below the hinge, said link being so proportioned in length when contracted as to serve as a brace for supporting the bowl in position for use and being moved across the line of the said hinge during the raising 105 of the bowl to elastically hold the bowl against the wall plate.
